(57) **CLAIM**

The ornamental design for a digital camera display panel with transitional graphical user interface, as shown and described.

DESCRIPTION

FIG. 1 is a front view of a first image of a digital camera display panel with transitional graphical user interface; FIG. 2 is an enlarged front view of the first image thereof; FIG. 3 is an enlarged view of a second image thereof; and, FIG. 4 is an enlarged view of a third image thereof.

The appearance of the transitional image sequentially transitions between the images shown in FIG. 2-4. The process or period in which one image transitions to another image forms no part of the claimed design.

The evenly spaced broken lines in FIG. 1 depict the article and form no part of the claimed design. The unevenly-spaced broken lines in all of the figures indicate the boundary of the claim and form no part of the claimed design.
